UNITED STATES PATENT OFFICE.

ALBERT EDWARD ROSE, OF ROTHERHAM, ENGLAND.

APPARATUS FOR PUSHING COAL TUBS.

Application filed September 16, 1924. Serial No. 738,107.

To all whom it may concern:

Be it known that I, ALBERT EDWARD ROSE, a British subject, residing at Stone Lea, Parkgate, Rotherham, Yorkshire, England, **5** have invented certain new and useful Improvements in Apparatus for Pushing Coal Tubs, of which the following is a specification.

This invention relates to improvements in **10** or connected with apparatus for unloading full and loading empty wagons or carves into the mine cages and of that kind in which pivoted pushing arms or the like are adapted to engage one or more wagons in **15** line or side by side on separate rails, and to push same into the cage, the said arms then returning to the initial or ready for use position and turning on their pivots into lowered positions to which the said arms or **20** equivalents are rocked or turned by their engagement with a fixed stop or stops adjacent to the rails, or according to one construction of my invention by tipping a bogie on which the arms are mounted.

25 These buffer arms can be actuated by hydraulic or other means, or I may employ compressed air, steam or an electric motor.

I will describe the invention more particularly as constructed for operation hydraulically and in which the fluid is charged into a cylinder fitted with a piston rod and piston. The cylinder is permanently fixed in a horizontal position preferably on the centre line of the machine, the piston rod end being secured to a bogie or travelling car which moves to and fro in a horizontal line, having suitable wheels which run in steel channels say between the two parallel sides of a steel girder of H section and which may advantageously form the framework of the **40** machine.

The machine can be used for cages where two or three wagons are charged into the cage side by side provided the framework is sufficiently wide to carry the bogie or travelling car necessary for each set of wagons.

The length of the framework is determined by the number and length of wagons **50** to be charged into the cage by one thrust of the machine.

Vertical arms are mounted on the bogie and are designed to suit the buffers of the

wagons, and there will be provided one arm with buffers attached to the top for each set of wagons to be charged side by side. The arms may be rigid with or pivotally attached to the bogie and when pivoted the hinge of the arm is fitted to the bottom of the bogie and in such manner that the arm **60** rests against the top side of the bogie, thus preventing it from moving from the vertical position when the machine is in operation.

If rigid arms are used the track on which the bogie travels is turned downwardly at **65** the rear or cylinder end of the travel and so tilts the bogie and turns the arm downwardly. The hinged buffer arm is held in a vertical position by a strong spiral spring preferably fitted into a tube connected to **70** the framework of the machine, and in such manner that the arm can by contact with a stop on the framework be lowered sufficiently at the end of the return stroke for it to be out of contact with the wagons which **75** are being put into position.

The movement of the bogie is obtained by moving a lever which is connected to a suitable valve. When the lever is moved in a forward direction the valve admits **80** fluid to the rear end of the cylinder. The pressure forces the piston, piston rod and bogie forward. The arm leaving the stop as the bogie moves forward is pulled by the spring into the vertical position (or **85** is turned upwardly by the bogie reassuming its horizontal position), when the buffers of the arm will come in contact with the buffers on the empty wagons and push them into the waiting cage, at the same time discharging the full wagons from the cage. The valve lever is then reversed, which admits the pressure to the front end of the cylinder, which pushes back the piston, piston rod, and bogie to the rear of the frame. To prevent the forward movement of the bogie when the cage is not in the position for being charged, a safety lever is placed in a suitable position and operates a catch, which secures the bogie, thus preventing it moving until **95** required.

As an additional safeguard the operating lever is held whilst the gate is down as by a projection or equivalent on the gate engaging the lever or an arm thereon.

I will now describe my invention with

reference to the accompanying drawings in which:

Figs. 1 and 1^a together show a partial side view of the apparatus and show also by line and dot a cage and wagons.

Figs. 2 and 2^a together show a plan view of the apparatus seen in Fig. 1.

Fig. 3 is a broken elevation, partly in section, showing the buffer arm at the operative limit of movement.

Fig. 4 is a similar view showing the buffer arm depressed to permit the wagons to pass thereover.

Fig. 5 is a broken front elevation showing the mounting of the bogie truck.

Fig. 6 shows an alternative means for tipping the buffer arm, and

Fig. 7 is a diagrammatic view showing a general lay-out of the apparatus.

Referring to Figs. 1 to 5 and Fig. 7, the cage *a* and wagons *b* are of the usual kind, and the latter are adapted to run on rails *c* into and out of the cage.

My apparatus comprises the cylinder 1 in which is a piston 2 with rod 3 connected to a bogie 4 adapted to travel to and fro on steel joists 5, see Fig. 5.

Attached to the front of the bogie is a pivoted buffer arm 6 to which a spring-controlled rod 7 is connected and adapted to hold the arm in vertical position. This spring is enclosed in a tube 8. A valve 9 is fixed to the cylinder 1 and is controlled by a lever 10 to which it is connected by an adjustable rod 11. Fluid pressure is admitted to the cylinder by pipe 12 and according to the position of the valve will thrust the piston one way or the other and thus move the bogie to or from the cage.

A cross bar or stop 13 is arranged to contact with the buffer arm when it approaches the end of its rearward travel and is adapted to push the arm downwardly against the spring action, and thus allow wagons to be pushed over the arm which rises on the initial outstroke of the piston rod and re-assumes its upright position so as to contact with the rearmost wagon and push it into the cage.

A gravity catch 14 is provided to engage the bogie when it reaches the end of its rearward travel. This catch is lifted by an arm 15 connected to the valve and so arranged that it is operative only when the lever 10 is moved to actuate the valve for the purpose of pushing the bogie forward.

The three positions of the lever are seen in Fig. 1. The foot of the lever has a shoddered plate adapted to engage a projection 16 movable by the gate of the cage when it is fully raised. The construction is such that with the gate down the lever cannot be moved to operate the piston for the forward movement of the bogie and thus collision between the wagons and the gate is averted.

The bogie may be adapted to strike the lever or a part connected to it when the bogie is close to the cage gate so as to reverse the lever and bring about the automatic return of the bogie or stop its forward movement.

In Fig. 6 an alternative means of turning over the buffer arm is illustrated diagrammatically. In this case the bogie shown at 20 has wheels or rollers 21 travelling on the steel joists 22 which are curved downwardly at the rear end of the bogie travel so as to tip the bogie and turn the buffer arm downwardly. This construction dispenses with the use of springs. The piston rod is shown at 23.

If electric power is employed in place of the hydraulic, steam or air, several methods of carrying out my invention may be adopted. As an example the bogie may be made to contact with a lever at about each end of its travel and these levers may control a reversible electric motor adapted to draw the bogie to and fro with safety means for preventing the forward movement until the wagons have been pushed into position. As another example, the bogie may carry a reversing gear which is actuated by contact with fixed stops so that its direction of travel is reversed at each end, or the bogie may carry a motor which drives a toothed wheel engaging a rack between the rails, said motor, or its drive, being reversed at both ends of travel.

What I claim is:

1. An apparatus for pushing empty wagons into mine cages, comprising a bogie truck adapted to travel to and from the cage, a buffer arm carried thereby, means to lower the arm in one position of the truck for permitting the wagons to travel over the arm, and means for holding the bogie truck against movement when the arm is lowered.

2. An apparatus for pushing empty wagons into mine cages, comprising a bogie truck adapted to travel to and from the cage, a buffer arm carried thereby, means to lower the arm in one position of the truck for permitting the wagons to travel over the arm, and means for automatically holding the bogie truck against movement when the arm is lowered.

3. An apparatus for pushing empty wagons into mine cages, comprising a bogie truck adapted to travel to and from the cage, a buffer arm carried thereby, means to lower the arm in one position of the truck for permitting the wagons to travel over the arm, and means for holding the bogie truck against movement when the arm is lowered, and means to prevent incorrect operation of the means for controlling the bogie truck when the latter is adjacent the cage.

4. An apparatus for pushing empty wagons into mine cages, including a bogie

truck adapted to travel to and from the cage, a buffer arm carried by the truck and adapted when in upright position to engage and push the wagons in the movement of 5 the bogie truck toward the cage, means whereby said arm is tilted when the bogie truck reaches a position of maximum travel from the cage, and means whereby the bogie truck is releasably held against movement 10 while the arm remains in tilted position.

5. Apparatus for pushing wagons into cages when at the mouth of mines, said apparatus comprising a fluid operated ram, a lever controlling the fluid pressure for the 15 ram, a bogie adapted to travel to and fro on rails between the ram and the cage, an arm on the bogie, means for raising the arm when the bogie moves towards the cage and means for lowering the arm when the bogie 20 moves towards the ram, automatic means for releasably holding the bogie when away

from the cage said automatic means being under the control of the said lever.

6. Apparatus for pushing wagons into cages when at the mouth of mines, said apparatus comprising a fluid operated ram, a lever controlling the fluid pressure for the ram, a bogie adapted to travel to and fro on rails between the ram and the cage, an arm 25 on the bogie, means for raising the arm when the bogie moves towards the cage and means for lowering the arm when the bogie moves towards the ram, automatic means for releasably holding the bogie when away 30 from the cage said automatic means being under the control of the said lever, and means controlled by the position of the cage for preventing improper movement of the controlling lever when the bogie is adjacent 35 the cage.

In testimony whereof I affix my signature.

ALBERT EDWARD ROSE.
